UNITED STATES PATENT OFFICE.

ISAAC A. BAUM, OF CHICAGO, ILLINOIS.

DOORFRAME.

Application filed April 27, 1928. Serial No. 273,305.

My invention relates to building construction and particularly to a novel buck and jamb arrangement involving the use of a metal buck and a wood jamb suitably joined 5 thereto.

In construction of the described type, it is customary to provide a metal buck of generally channel shape, the channel being open toward the door opening, a plurality of wood 10 blocks being seated and secured in the channel to provide means for attachment of the jamb. Notwithstanding the most careful fitting of the jamb and molding to the rough buck, there will be points in the length of the 15 frame where a through opening cannot be avoided and consequently light and air will pass through said opening. This is particularly liable to occur at points between the wood blocks, at which points there is no filing 20 between the metal buck and the jamb.

My invention contemplates the employment of simple means that will obviate the possibility of any open space between the metal and wood members through which light 25 and air can pass.

My invention will be more readily understood by reference to the accompanying drawings, in which—

Fig. 1 is a sectional view through a buck 30 and jamb arranged in accordance with my invention;

Fig. 2 is a perspective view of a buck and wood block;

Fig. 3 is a sectional view through a modified form of my invention, and

Fig. 4 is a perspective view of the construction shown in Fig. 3.

In the drawings and referring particularly to Figs. 1 and 2, I have illustrated a metal 40 rough buck in the form of a channel having a web 10, flanges 11 and plaster terminal flanges 12, terminating in rebent margins 13 serving as a plaster anchor. A wood block 14 is seated in the channel, a plurality thereof 45 being preferably employed, in spaced relation. The thickness of the block in this construction must be less than the depth of the flanges of the channel, thereby leaving a recess or pocket to receive the continuous projection 15 from the jamb 16. In other words, 50 by making the block of less depth than the buck flanges, the jamb is compelled to enter

and occupy a space within the limits of the flanges and thereby to effectually prevent the passage of light transversely through the 55 joint. Preferably the jamb has integral molding 17 that snugly fits against the flanges 12 of the buck. In order to insure a perfect fit against the face of the flanges 12, I preferably proportion the wood block so that a 60 small space is provided between it and the corresponding face of the jamb. The construction described provides an extremely simple means of accomplishing the purpose and provides an especially desirable arrangement from a construction standpoint. 65

In the construction shown in Figs. 3 and 4 the buck is identical with that already described. It has, however, in addition to the elements described a continuous flat strip of 70 metal 16 welded to the inside face of one or both of the flanges 11 of the channel and projecting a substantial distance outside of the limits of the flanges. In this construction, the wood blocks 19 are shown as projecting 75 outside of the limits of the channel, although this is a matter of unconcern to the builder. At any rate the jamb 20 is directly abutted against the block and suitably nailed thereto. Thereafter the molding 21 is placed in the 80 position shown, overlying the metal strip and serving to finish the opening. Obviously an integral jamb and molding could be used by providing a longitudinal kerf at the point of register with the strip 18 in which case the 85 wood block would of necessity be of less thickness than the depth of the flanges. The construction shown will, however, adapt itself most readily to installation by the ordinary carpenter. If desired the strip 18 may be provided on both sides, thereby insuring the accurate placing of the jamb. In either case the strip serves to effectually exclude the passage 90 of light and air through the wall at the joint.

Obviously other modifications than that 95 shown may be made without departure from the spirit of my invention.

I claim:

1. In building construction, the combination of a channel shaped buck, a wood block 100 secured therein, the thickness of which is less than the depth of the flanges of the channel, and a jamb secured to the wood block and having a substantially continuous portion

projecting into the channel, whereby the joint between the block and jamb is within the limits of the flanges.

2. In building construction, the combination of a channel shaped buck, a wood block secured therein, the thickness of which is less than the depth of the flanges of the channel, and a combined jamb and molding secured to

the block the jamb having a continuous portion projecting into the channel whereby the joint between the block and said portion is within the limits of the flanges. 10

In testimony whereof I have affixed my signature.

ISAAC A. BAUM.
